SINGLE LEVER SAW SWAGE

Don Daboll, Durango, Colo.

Application September 7, 1951, Serial No. 245,475

8 Claims. (Cl. 76—54)

1

This invention relates to new and useful improvements in saw swages and the primary object of the present invention is to provide a saw swage including a single lever for actuating a clamping means and a die and thereby avoiding the necessity of employing a lever for the clamping means and a second lever for operating the die.

Another important object of the present invention is to provide a saw swage including a clamping means and a die that are both operatively connected to a single lever whereby the clamping means and die will be actuated in sequence as the lever is swung in one direction.

A further object of the present invention is to provide a saw swage so constructed as to avoid the heretofore four step operation of a two lever saw swage through the medium of a single lever and novel and improved means operatively connecting the lever to a clamping means and a die holder.

A still further aim of the present invention is to provide a saw swage of the aforementioned character that is simple and practical in construction, strong and reliable in use, small and compact in structure, efficient and durable in operation, inexpensive to manufacture, service and assemble, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the invention showing the operating handle in a back position;

Figure 2 is a side view taken from the other side of Figure 1 and showing the lever in a front position;

Figure 3 is a view similar to Figure 2 but showing the lever in a back position;

Figure 4 is an enlarged detail vertical sectional view taken substantially on the plane of section line 4—4 of Figure 2; and,

Figure 5 is an enlarged detail vertical sectional view taken substantially on the plane of section line 5—5 of Figure 4.

Referring now to the drawings in detail, wherein for the purpose of illustration, there is disclosed a preferred embodiment of the present invention, the numeral 10 represents a cylindrical swage block having a peripherally disposed radial slot 12 that will accommodate the toothed edge E of a saw S.

2

A plate 14 at the inner end of the back support arm 16 is secured against one face of the block 10 by fasteners 18 that extend through arcuate slots 20 in the plate 14 to receivably engage threaded apertures in the block. An arcuate flange 22, forming part of the plate 14, extends about a portion of the periphery of the block 10 and this flange is secured to an arcuate flange 24 at the inner end of a front arm 26 by fasteners 28.

The outer end of arm 16 is provided with lateral projections 30 that will extend behind and in front of the saw being swaged and the outer end of the arm 16 supports a hand grip 32 to which there is removably secured a back pressure foot 34 that parallels the arm 16. The outer end of arm 26 adjustably supports a front pressure foot 36 that normally parallels arm 26 and which is coplanar with pressure foot 34, whereby the pressure feet may rest upon the toothed edge of a saw with the block straddling the toothed edge.

A bearing 38 is removably secured to the outer periphery of the block 10 and comprises a mounting flange 40 that is secured by fasteners 42 in a flat recess 44 in the outer periphery of the block 10. The bearing 38 also includes a pair of longitudinally spaced, co-axial sleeve sections 46 that are connected rigidly to the flange 40 by webs 48.

Sleeve sections 46 rotatably support a short shaft 50 whose ends project outwardly beyond the sleeve sections 46. The hub portion 52 of a lever 54 receives the central portion of shaft 50 and is suitably keyed thereto, the lever being located between the adjacent ends of the sleeve sections, whereby the shaft may be rotated upon manually swinging the lever.

A die holder 56 is supported for rotation adjacent one side of the block 10. This die holder includes an arm 58 having a bifurcated end 60 that pivotally supports a sleeve 62 between its furcations. The end of the arm 58 remote from the bifurcated end 60 is formed with an opening 45 that accommodates the threaded end of a holding member 63. A nut 64 is threaded on the threaded end of member 63 to hold the same to the arm 58 and a die D is suitably held in the axial bore in the member 63 and extends through an opening 66 in the block 10 that intersects the slot 12 as shown in Figure 5.

Means is provided for connecting the die holder to one end of the shaft 50. This means assumes the form of a link element 68 having one end 55 keyed over one exposed end of the shaft 50. The

other end of the link element is bifurcated to receive therein the eye end 70 of a rod 72 that is pivoted to the link element by a pin 74. Rod 72 is slidably received in a transverse aperture in the central part of sleeve 62 and threadingly carries abutments 76 for engaging the sleeve 62 in order to rotate the die holder 56.

The block 10 is provided with a pair of aligned internally threaded openings 78 and 80 that receivably engage companion clamping members or screws 82 and 84 as shown in Figure 4. The openings 78 and 80 intersect slot 12 and the members 82 and 84 are movable into and out of the slot 12, the member 82 being initially adjusted and the member 84 being adjusted by a mechanism during operation of the tool, which mechanism will now be described.

The elongated multi-sided end 86 of the member 84 fits into a corresponding multisided bore in a sleeve 88 having a flange 90 at its inner end. A second sleeve 92 is rotatable on and embraces sleeve 88 and the outer end of sleeve 92 is integrally formed with an arm 94 disposed perpendicular to the member 84 and parallel to the lever 54. A torsion spring 96 surrounds the sleeve 92 and its ends enter accommodating apertures in the flange 90 and the arm 94.

A pin 98 carried by the flange 90 extends under and parallels the sleeve 92 and will be engaged by a lug 100 on arm 94 as the arm 94 is rotated in one direction. One of the fasteners 18 is formed with an angulated stop forming end 102 that will be engaged by arm 84 to limit swinging movement of the latter toward the back arm 16.

The outer end of arm 94 supports a laterally projecting roller or headed pin 104 on whose shank is positioned a washer 106 having a peripheral tooth receiving notch 108 for a purpose later to be described.

Means is provided for rotating the member 84 whereby a saw may be selectively held between and released from the screw 82 and member 84. This means consists of a cam 110 that is keyed on the other end of the shaft 50. The cam 110 has an outer edge 112 forming a track for roller 104 and a groove 114 in its outer face also forming a track for the roller 104.

A finger 116 forms part of the cam 110 and supports a catch 118 including a spring 120 that will prevent reentrance of the roller 104 in the groove 114 after the roller has passed completely through the groove 114. The spring 120 is secured to and coiled about a fastener 122 of the catch and includes an arcuate portion 124 extending across one end of the groove 114 and terminating in a lip or abutment 126 for roller 104.

The face of the cam 110 having the groove 114 is formed with a protuberance or tooth 128 for engaging the previously mentioned notch 108 whereby the pin or roller may have sufficient clearance to pass through the curved groove 114.

A stop holder 130 secured to block 10 adjustably carries a set screw 132 that will limit swinging movement of the member 84 toward the support arm 16.

In practical use of the present invention, the toothed edge of the saw is placed in slot 12 and the pressure feet 34 and 36 rest upon the toothed edge of the saw. The handle or lever 54 is positioned in its front position and toward arm 16 as shown in Figure 2.

When lever 54 is pulled back toward arm 16 link member 68 swings forwardly toward arm 26 and abutments 76 engage sleeve 62 to swing the

die holder 56 forwardly whereupon the die D swages the saw tooth.

During the backward movement of lever 54 and prior to actuation of the die holder sufficiently to swage the saw tooth, the pin 104 passes along edge 112 of cam 110. The arm 94 is thus rotated forward and is held in a forward position until lever 54 is moved almost to its extreme back position. Since arm 94 is connected to clamp screw 84 by torsion spring 96, the screw 84 is secured against the saw and held there by the spring. When lever 54 is pulled completely back, the spring 96 moves arm 94 backward until pin 104 enters curved groove 114.

As lever 54 is moved forwardly, pin 104 passes along curved slot or groove 114 and passes through catch 118. The catch prevents return of the pin 104 in groove 114. The safety tooth on the cam and the slot 108 in washer 106 facilitate the passage of the pin 104 through the groove 114. While the pin 104 is passing through the groove 114, the clamp screw 84 is unscrewing.

Having described the invention, what is claimed as new is:

1. A single lever saw swage comprising a swage block having a peripheral slot therein adapted to accommodate the toothed edge of a saw, a bearing supported on the block and disposed perpendicular to the slot, a shaft rotatably mounted in the bearing, a lever secured to the shaft for rotating the latter, a die holder rotatably mounted on said block, said block having an opening intersecting said slot and adapted to rotatably receive a die carried by the holder, means disposed on one side of the block connecting one end of said shaft to said holder for rotating the holder during swinging of the shaft, a clamping member, said block having another opening intersecting the slot and receiving the clamping member, and means disposed on the other side of the block connecting the clamping member to the other end of the shaft for movement of the clamping member as the lever is swung, said last mentioned connecting means including a cam secured to the shaft and a roller attached to the clamping member engaging the cam.

2. A single lever saw swage comprising a swage block having a peripheral slot therein adapted to receive the toothed edge of a saw, a bearing supported on the block and disposed perpendicular to the slot, said bearing having a pair of co-axial longitudinally spaced sleeve sections, a shaft rotatably supported in said sleeve sections, a lever secured to the shaft between the adjacent ends of the sleeve sections for rotating the shaft, said block having an opening intersecting the slot, a die holder rotatably supported on one side of the block and adapted to hold a die that is extended through the opening and into the slot, means connecting one end of the shaft to the die holder to rotate the latter in response to swinging movement of the lever, a clamping member carried by the other side of the block and movable into and out of the slot, and means operatively connecting the other end of the shaft to the clamping member for selectively moving the clamping member into and out of the slot as the lever is manually swung.

3. The combination of claim 2 wherein said means connecting said shaft to said die holder includes an arm projecting laterally from said shaft, a link pivoted to the arm and slidably secured to the die holder, and an abutment on the link adapted to engage and rotate the die holder as

the lever is rotated to move the arm toward the die holder.

4. The combination of claim 2 wherein said block is provided with a threaded opening receivably engaging said clamping member, said means connecting said clamping member to said shaft including a sleeve rotatable with said clamping member, a link member rotatable on the sleeve, and a torsion spring about the sleeve and terminally secured to the sleeve and the link member.

5. The combination of claim 4 wherein said means connecting said clamping member to said shaft includes a roller supported on the link member, a cam secured to and rotatable with the shaft and engaging the roller as the shaft is rotated by the lever in order to impart rotation to the link member and the clamping member.

6. The combination of claim 5 wherein said cam is provided with an outer edge riding against the roller as the lever is swung in one direction, said cam being provided with a groove receiving the roller as the lever is rotated in an opposite direction.

7. The combination of claim 6 and a catch restricting reentrance of the roller in the groove after the roller has passed completely through the groove and toward said outer edge.

8. The combination of claim 7 and interconnecting means between the link member and the cam, said interconnecting means comprising a washer carried by the link member having a peripheral notch and a tooth on the cam adapted to enter the notch upon rotation of the lever to permit the roller to pass through the groove.
